REINFORCED BRAKE-BEAM.

1,060,140.

Specification of Letters Patent. Patented Apr. 29, 1913.

Application filed August 19, 1912. Serial No. 715,710.

To all whom it may concern:

Be it known that I, JAMES S. SHEAFE, a citizen of the United States, residing at the city of Chicago, in the county of Cook and 5 State of Illinois, have invented certain new and useful Improvements in Reinforced Brake-Beams, of which the following is a specification.

This invention relates to new and useful 10 improvements in brake-beams, and has for its object to provide an improved brake-beam in which parts of minimum size are utilized and united to produce a structure of maximum strength and efficiency.

15 In the accompanying drawings forming part of this specification, in which like numbers of reference denote like parts wherever they occur, Figure 1 is a top plan view of an improved brake-beam embodying the 20 present invention; and, Fig. 2 is a sectional view, on an enlarged scale, on the line 2—2, Fig. 1.

The brake-beam of the present invention consists of an I-beam 1, to the ends of which 25 are riveted, bolted, or otherwise secured the brake-heads 2 which support the brake-shoes (not shown in the drawings) in the usual manner. The brake-beam is suspended in the usual manner from the framework 30 of a car or other conveyance (not shown) so that the web of the I-beam is substantially horizontal, and has a pair of plates 3 secured thereto by means of the rivet 4 or the like, which passes through openings in 35 each plate 3 adjacent to an end thereof and, also, through an opening in the web of the I-beam 1 at a point in the middle of said I-beam and near the flanges 5 borne by the particular side of said I-beam on 40 which the brake-heads are located. The end portion of one of the plates 3 that is secured to the web of the I-beam 1 by the rivet 4 is bent so as to fit snugly against the upper flange 5 and the upper 45 surface of the web of the I-beam 1, and the same end portion of the other plate 3 is similarly bent so as to fit snugly against the lower flange 5 and the lower surface of the web of said I-beam as clearly illustrated in 50 Fig. 2. The plates 3 extend outwardly from the flanges 5 and are twisted in the usual manner in order to grip said flanges tightly, the free ends of said plates being spaced apart so as to receive the brake-rod (not 55 shown) therebetween and having register-

ing openings 6 to receive a bolt or rivet (not shown) or a plurality of bolts or rivets by means of which the brake-rod is secured to said plates in the usual manner. The other side of the I-beam 1 that bears the flanges 7 is subjected to strains of compression by the pull of the brake-rod upon the plates 3, and in order to strengthen the I-beam, so as to prevent the pull upon said plates from causing the I-beam 1 to bend between the brake-heads 2, an angle-iron 8 is provided and is secured to the web of said I-beam by means of rivets 9 or the like. The angle-iron 8 is preferably arranged to extend substantially parallel to the flanges 7 borne by the I-beam 1 and, also, so that the leg of same that projects outwardly from the web of said I-beam is near one of the flanges 7, while the other leg of said angle-iron that is riveted to the web of the I-beam 1 extends toward the end of the particular plate 3 on the same side of the web with said angle-iron, the end of said plate 3 being beveled at 10, so as to overlap the edge of the riveted leg of the angle-iron 8, which edge of said angle-iron is, also, beveled at the point where the beveled end of said plate 3 overlaps same, as depicted in Fig. 2.

Heretofore, when a brake-beam formed of an I-beam was reinforced by an angle-iron, it was necessary to form a cut-away part in the riveted leg of the angle-iron in order to allow the riveted end of one of the brake-rod-connecting plates 3 to fit therein. This was due to the fact that the riveted leg of the angle-iron was wider than absolutely necessary and, also, that an excess of metal was left between the rivet 4 and the end of the plate 3. These features made the cost of manufacturing the brake-beam more than was absolutely necessary, but have been obviated by the present invention so that the cost of manufacturing such brake-beams has been reduced to the minimum, due to the fact that the riveted leg of the angle-iron 8 is narrower than ordinarily used, while at the same time is of ample width to add the necessary strength to the I-beam 1 and, also, that less metal is left between the rivet 4 and the end of the brake-rod-connecting plate 3 than the usual amount, but at the same time is sufficient to withstand the strain to which the plate 3 is ordinarily subjected, so that the end of said 110

plate merely touches and slightly overlaps the edge of the riveted leg of the angle-iron 8 as hereinabove described, thereby obviating the necessity of forming a cut-away portion in the riveted leg of said angle-iron.

In actual practice it has been found that after a brake-beam formed of an I-beam without any reinforcing has become bent from use and then heated and straightened, 10 the strength of the straightened I-beam is approximately eighty-six per cent. of the original strength of the I-beam, but when the straightened I-beam is reinforced by an angle-iron in the manner hereinabove described, 15 the strength of the reinforced I-beam is approximately twenty-nine per cent. greater than the original strength of the I-beam. For example a brake-beam formed of a 5" I-beam of light section with- 20 stood a test of 16,010 pounds maximum pressure, but after same was bent and then heated and straightened it withstood a test of 13,830 pounds maximum pressure, or approximately eighty-six per cent. of its original strength. After the straightened I- 25 beam was reinforced by a $2\frac{1}{2}$ " x 2" angle-iron $54\frac{1}{2}$ " long, the reinforced brake-beam withstood a maximum pressure of 20,690 pounds, or in other words the strength of 30 the reinforced brake-beam was approximately twenty-nine per cent. greater than the original strength of the I-beam. It has also been found in actual practice that a 35 brake-beam formed of an I-beam which has become bent from use can be straightened and reinforced at a relatively smaller cost than the original cost of the I-beam alone.

I claim:

1. A reinforced brake-beam embodying 40 an I-beam having brake-heads secured to the ends thereof, an angle-iron secured to the web of said I-beam and extending longitudinally of same, and a brake-rod-connecting plate located intermediate the brake-heads and secured to the web of said I-beam so that one end of said plate touches the edge of the leg of said angle-iron that is secured to the web of said I-beam.
2. A reinforced brake-beam embodying an 45

I-beam having brake-heads secured to the ends thereof, an angle-iron secured to the web of said I-beam and extending longitudinally of same, and a pair of brake-rod-connecting plates located intermediate the brake-heads and secured to the web of said I-beam so that the end of one of said plates touches the edge of the leg of said angle-iron that is secured to the web of said I-beam.

3. A reinforced brake-beam embodying an 60 I-beam having brake-heads secured to the ends thereof, an angle-iron secured to the web of said I-beam and extending longitudinally of same, and a brake-rod-connecting plate located intermediate the brake-heads 65 and having one end thereof secured to the web of said I-beam, the secured end of said plate being beveled to overlap part of the leg of said angle-iron that is secured to the web of said I-beam.

4. A reinforced brake-beam embodying an I-beam having brake-heads secured to the end thereof, an angle-iron secured to the web of said I-beam and extending longitudinally of same, and a brake-rod-connecting 75 plate located intermediate the brake-heads and having one end thereof secured to the web of said I-beam and beveled to overlap part of the edge of the leg of said angle-iron that is secured to the web of said I-beam, said part of the edge of the secured leg of said angle-iron being, also, beveled.

5. A reinforced brake-beam embodying an I-beam having brake-heads secured to the ends thereof, an angle-iron secured to the 85 web of said I-beam and extending longitudinally thereof, and a pair of brake-rod-connecting plates located intermediate the brake-heads and secured to the web of said I-beam, the end of one of said plates being 90 beveled to overlap a beveled part of the edge of the secured leg of said angle-iron.

In testimony whereof I hereunto affix my signature in the presence of two witnesses.

JAMES S. SHEAFE.
